Primary Examiner — Susan Moon Lee*(74) Attorney, Agent, or Firm* — QuickPatents; Kevin Prince**CLAIM**

I claim the ornamental design for a leash, as shown and described.

DESCRIPTION

FIG. 1 is a perspective view of a leash, showing the new design in an extended configuration;
 FIG. 2 is a perspective view thereof, illustrated in a compact configuration;
 FIG. 3 is a perspective view thereof in a flat configuration;
 FIG. 4 is a front elevational view of FIG. 3;
 FIG. 5 is a rear elevational view of FIG. 3;
 FIG. 6 is a top plan view of FIG. 3;
 FIG. 7 is a bottom plan view of FIG. 3;
 FIG. 8 is an enlarged left-side elevational view of FIG. 3; and,
 FIG. 9 is an enlarged right-side elevational view of FIG. 3. Broken lines and unshaded portions contained within broken lines are not claimed.
